UNITED STATES PATENT OFFICE.

EUGENE L. SCHELLENS, OF POINTE CLAIRE, QUEBEC, CANADA, ASSIGNOR, BY MESNE ASSIGNMENTS, TO C-S ENGINEERING COMPANY, A CORPORATION OF DELAWARE.

DRAFT APPLIANCE FOR LOCOMOTIVES.

Application filed April 28, 1925. Serial No. 26,358.

This invention relates to draft improvements in locomotives, and the nature, object and advantages of my invention will be best understood from the following:

- 5 In carrying out my invention I employ a draft appliance A of the kind disclosed in the copending application of Joel S. Coffin, Jr., and myself, Serial No. 681,450, filed December 18, 1923. This draft device is used 10 in place of the usual nozzle arrangement, the draft being created by a fan, diagrammatically indicated at 7, which fan is preferably operated by exhaust steam. The fan produces a more or less continuous draft 15 which may be of relatively low velocity but relatively large volume and I have discovered that the fan, by reason of its momentum, continues to revolve for a considerable period after the throttle is closed and the 20 locomotive engines are no longer receiving steam. In consequence of this there is quite a pull on the fire for some moments after throttle closure and this produces heavy pop losses.
- 25 It is, therefore, one of the primary objects of my invention to overcome the difficulty above set forth in a locomotive drafted by such a draft appliance.

How the foregoing, together with such 30 other objects and advantages, as may herein-after appear, or are incident to my invention, is obtained, is illustrated in the accompanying drawings, wherein

Fig. 1 is a diagrammatic side elevation of 35 a locomotive in which my improvements are embodied, certain of the parts being broken out;

Fig. 2 is an enlarged fragmentary side elevation of certain details of my invention; 40 Fig. 3 is a section taken on the line 3—3 of Fig. 2;

Fig. 4 is an elevation illustrating still other details of the invention; and

Fig. 5 illustrates a modification of the invention.

Referring now to Fig. 1, the reference numeral 8 indicates the locomotive boiler, the reference numeral 9 the fire-box and the reference numeral 10 the front end or smokebox. The cylinders and valve chests are 50 respectively indicated at 11 and 12, exhaust

steam being supplied to the draft device thru the pipes 13 and passages 14. The locomotive throttle is shown at 15 and the dry-pipe at 16. The fire-box has the usual ash-pan 17, but the opening between the fire-box and the ash-pan is closed by dampers 18.

When the throttle 15 is open and the locomotive is working steam, the dampers 18 are held in open position by means of a pressure operated device 19 which may be of any desired construction and to which pressure is supplied from the dry-pipe by means of the connection 20. The pressure admitted to the device 19 rocks the shaft 19^a, the opposite ends of which are connected to the dampers on opposite sides of the fire-box thru the medium of the links 21. When the throttle 15 is closed and pressure is, therefore, no longer supplied to the device 19, 70 the damper is closed by gravity, thus checking the draft. In consequence of this, even tho the fan may continue to rotate for some time after the throttle is closed, the fire is checked and pop losses are avoided. 75

If desired, the blower line may also be connected to the device 19 (see Fig. 5) by the pipe 22 so as to open the dampers when blowing up the fire when standing. In that event two check valves 23 and 24 are provided so as to ensure proper flow of steam to the device 19. 80

I claim:

1. In a locomotive, the combination of a grate, a fire box which receives its air through said grate, a draft creating fan operated by exhaust steam, fire box damper means for controlling such air automatically operating to check the fire when the throttle is closed to compensate for the rotation of said fan after said throttle is closed. 85

2. In a locomotive, the combination of a steam supply line, a blower line, draft creating means, fire box damper means, automatic control means for said damper means, a connection from the steam supply line to said control means, a connection from the blower line to said control means and a check valve in each of said connections. 95

In testimony whereof, I have hereunto signed my name.

EUGENE L. SCHELLENS.
